His Attorney.

UNITED STATES PATENT OFFICE.

SAMUEL E. GUINN, OF JOHNSON CITY, TENNESSEE, ASSIGNOR TO S. E. GUINN MANUFACTURING COMPANY, INC., A CORPORATION OF NEW YORK.

SHAVING BRUSH.

Application filed January 22, 1920, Serial No. 353,132. Renewed June 21, 1922. Serial No. 569,880.

To all whom it may concern:

Be it known that SAMUEL E. GUINN, a citizen of the United States, residing at Johnson City, in the county of Washington 5 and State of Tennessee, has invented certain new and useful Improvements in Shaving Brushes, of which the following is a specification.

This invention relates to improvements in 10 shaving brushes.

The prime object of the invention is to provide a brush with a reservoir for receiving plastic soap, and means for ejecting same into the bristles, and so arranging 15 the parts as to form a vacuum in the reservoir to withdraw surplus soap after use of the brush, to prevent waste.

A further object of the invention is to provide a brush mounting to permit of the 20 convenient assemblage or separation of the parts to maintain the brush in a sanitary condition.

A still further object of the invention is to provide a brush structure having a plastic 25 soap reservoir, and a powder container which is absolutely water-proof.

Another object of the invention is the provision of duct or tubular means for expressing the soap to the bristles, and arranging 30 the brush head and associated parts to form a frictional grip between the handle, brush head and tubular means for convenience in holding the elements together.

The invention also comprehends improvements in the details of construction and arrangement of parts which will be herein-after described and particularly pointed out in the claims.

In the accompanying drawing:

40 Fig. 1 is a side elevation of my improved brush.

Fig. 2 is a vertical, central section of the same.

Fig. 3 is a detailed prospective view of 45 the combined powder container and soap plunger.

Fig. 4 is a detailed view of the brush head.

The numeral 1 indicates a cylindrical reservoir which is internally threaded as at 50 3. Engaging the threads 3 at the lower end of the reservoir is an inverted bottom cup member 4, provided with a shoulder 5, against which the lower edge of the cylindrical reservoir seats. The cup member 4 is hollow on its under side, as shown at 6,

and is further provided with a central tube 7, which extends below the plane of the bottom edge of the cup member. The top of the cup member is flat, and forms the bottom wall of the reservoir, and the opening 60 through the tube communicates with the said reservoir to provide a passage for the plastic soap.

Fitting within the hollow portion 6 of the cup member, is a brush head 8, formed with 65 a central opening 9, and hollow on its under side, as shown at 10. Depending centrally in the hollow portion 10, is an outwardly tapering projection 11, through which the opening 9 extends, and the inner side wall 70 of the hollow portion of the head is corrugated as at 12.

The bristles forming the brush are forced into the hollow portion 10, and are confined between the tapered wall 11, and the corrugated wall 12 which serves to maintain 75 said bristles in the fixed position in the head. By this construction a cavity 13, is formed in the center of the bristles to receive a rubber or other flexible tubular member 14, frictionally supported on the tube 7. The opening 9, in the brush head is of sufficient diameter to permit the tubular rubber member 14, to pass therethrough when the parts are assembled, as clearly shown in 80 Fig. 2.

The brush head frictionally engages the wall 6 of the bottom cup member, while the wall of the opening 9, frictionally engages the rubber tubular member 14. This frictional engagement between the head and the cup member forms a means for holding the brush in fixed relation, and is one which permits ready and convenient assemblage 90 or removal of the parts. Engaging the threads 3, of the cylindrical reservoir 1, is a hollow plunger 16, formed at its lower end with a threaded portion 17, and provided at its upper end with threads 18, below which is an annular flange 19. Snugly 100 fitting over the cylindrical reservoir 1 is a sleeve 20, the upper end of which engages with the flange 19, and in the sleeve, below the flange are vent openings 21, to permit the exit of air as the plunger is adjusted in or out in the reservoir, when using the brush. This sleeve constitutes an enclosing or finishing member between the cylindrical reservoir 1, and the hollow plunger, while the openings 21 prevent the accumulation of 110

foul air in the space 22, between the sleeve and the plunger. As the plunger is moved in and out, air is drawn in and forced out through the openings 21, which tends to retain the parts in a sanitary condition.

The upper end of the hollow plunger is interiorly screw-threaded, as at 23, and engaging the same is a cup shaped cover 24, provided with an opening 25. Fitting over 10 the cover, and engaging the threads 18, on the plunger is a cap 26.

Assuming the parts are in the position shown in Fig. 2 and plastic soap is in the reservoir between the bottom of the plunger 15 16, and the bottom cup member 4, and powder is in the hollow portion of the plunger 16, by turning the cap 26, it engages the flange 19, and forces the sleeve down on the outer surface of the plunger and expels 20 the air from between the parts through the openings 21, and also forces the plunger down on the soap and expels the same through the tubes 7 and 14 and into the center of the bristles. Obviously, when the 25 bristles are moistened, the plastic soap is converted into lather, the rubber tube readily yielding when the brush is used.

After the brush has been used, the plunger is rotated slightly in the opposite direction, which creates a partial vacuum in the 30 reservoir, the excess plastic soap in the tubes being thereby withdrawn into the reservoir, so that when the bristles are subsequently washed, there is no chance of the soap remaining 35 in the bristles, thus avoiding the possibility of an unsanitary condition arising with the bristles.

The construction described has been designed to produce a practical, convenient 40 and sanitary shaving brush. It follows from the foregoing description that the expulsion of the plastic soap into the bristles will be such that the soap will be sustained within the bristles until worked up into 45 lather, and that liability of the soap being retained in the bristles after the plunger is withdrawn is practically impossible. The hollow plunger contains powder, and after shaving the cap is removed from the handle 50 and the brush is inverted and the powder is sifted through the opening 25. The ar-

rangement of the cover 24, prevents undue waste of the powder, and when the cap is applied it serves as a cover for the opening as well as a convenient knot for rotating 55 the plunger.

What I claim is:

1. A shaving brush comprising a handle, an inverted cup arranged in the lower end of the handle and having a central tube projection opening thru the cup, a flexible tube fitting over the tube projection and extending below the same, a brush head having a wall fitted within the inverted cup and an annular projection within said wall adapted to overlie the flexible tube to bind said flexible tube between said wall and the wall projection of the cup, the space between the wall and annular projection of the brush head being formed to receive the brush 70 bristles. 65

2. A shaving brush comprising a handle formed at its lower end with an inverted cup from which depends a tube, a rubber tube forced on the first mentioned tube, a 75 hollow brush head having a central projection formed with an opening, the rubber tube frictionally engaging the wall of the opening and the side of the brush head frictionally engaging the wall of the inverted 80 cup on the handle to lock the head and handle together, and a plunger in the handle to force soap through the tubes to the bristles. 85

3. A shaving brush comprising a hollow internally threaded handle, an inverted cup 90 having a reduced portion externally threaded and engaging the internally threaded portion of the handle, the inverted cup having a central reduced tubular extension, a flexible tube frictionally held on the tubular 95 extension and depending below the latter, a brush head having a central projection, the brush head frictionally engaging the walls of the inverted cup and the central projection frictionally engaging the flexible tube and binding the same on the tubular extension of the cup, whereby to hold the brush head on the handle, and a plunger for forcing soap thru the tube to the bristles of the brush. 100

In testimony whereof I affix my signature.
SAMUEL E. GUINN.
